UNITED STATES PATENT OFFICE.

EDWIN CHESTERMAN, OF ROXBURY, MASSACHUSETTS.

IMPROVED WRINGER AND WASHING-MACHINE.

Specification forming part of Letters Patent No. 58,215, dated September 25, 1866.

To all whom it may concern:

Be it known that I, EDWIN CHESTERMAN, of Roxbury, Norfolk county, State of Massachusetts, have invented a new and useful Improvement in Machines for Washing and Wringing Clothes; and I do hereby declare that the following is a full, clear, and exact description thereof, which will enable others skilled in the art to make and use the same, reference being had to the accompanying drawings, forming part of this specification, in which—

Figure 1 is a front elevation of a washing and wringing machine made according to my invention, a portion of the frame having been taken away to show one of the springs above the journals of the upper roller. Fig. 2 is an end view. Fig. 3 is a cross-section, on the line α of Fig. 1, of the rollers of the machine. Fig. 4 is a detailed view of the cam which operates the rollers when the machine is used for washing clothes.

Similar letters of reference indicate like parts.

The object of this invention is to produce a machine for washing and wringing clothes which shall be compact in form, simple in operation, and easily operated. The invention embraces several particulars, one of which relates to the form of the cam, by which motion is communicated to the working or pressing rollers of the machine. Another relates to the manner of working the shafts on which the elastic covering of the rollers is mounted. Another relates to the manner of setting the crank so that it can be turned without coming in contact with the rim or sides of the tub or vessel to which the machine is attached. Another relates to the clamps by which the machine is fastened to the sides of a tub. Another relates to the manner of producing pressure upon the ends of the shaft of the upper roller.

The letter A designates the frame of the apparatus or machine, the end or upright parts of the frame being slotted to receive the journals of the rollers, the journals of the lower one resting in the bottom of the slot, and those of the upper one being free to move up and down in the slots, only restrained by a spring-bar, G, whose ends enter the slots

and rest there on elastic cushions or springs H H, of rubber, that are fastened to half-boxes L L, which slide in the slots and rest on the journals of said upper roller. The spring-bar G extends the whole length of the frame, and is placed beneath the upper rail, F, thereof, a temper-screw, which goes through the rail, serving to force the bar downward when the upper roller is to be brought against the lower one with increased pressure.

The top rail, F, is connected to the upright ends of the frame by means of a dovetailed joint, as shown in Fig. 2, in order to prevent the rail from becoming split from the effects of the strain put on this part of the machine when in operation.

The springs H, which in this example are made of rubber, may be of metal if preferred.

The bottom of the frame is provided with two sets of round fingers, K K', one at each end of the frame, which fit over the edge or rim of a tub, the fingers K being fixed and the fingers K' being capable of rotation in sockets J J, which are formed on the end of iron plates that are permanently fastened to the frame, that part of each finger K' which is between the sockets being provided with a shoulder which prevents it from having motion endwise. The fingers K' are provided with set-screws, which serve to clamp the machine fast to a tub.

The shafts in those parts which are covered with the elastic material B are made with four radial arms at right angles to each other, forming a "spider" or skeleton, B', whose circumference is the elastic covering B. The angular spaces between the arms of the spider are filled with angular blocks B², which are thicker radially than the angular spaces in which they are placed, thereby forming a depression between adjacent blocks along the line of each of the arms of the spider lengthwise of the shaft, which depressions will be occupied by the elastic coverings, so as to lock it and prevent it from turning on the shaft. The ends of each shaft have caps C, which are permanently fastened thereon, and serve to hold the blocks in place, and also the elastic covering B.

One end of each roller-shaft has a wheel, D, whose outer face is furnished with teeth near

its periphery, which are engaged by the said worm E, the flanges of the worm being wide enough to engage the teeth of both worm-wheels D, even when the distance between said wheels is somewhat increased by the passage of clothes through them. The worm E gives a continuous rotary motion to the roller-shafts, and it is therefore to be employed when the machine is used as a clothes-wringer. The shaft of the worm is properly supported in brackets that project from the frame A, and on one end of said shaft is placed the crank I, the arm of which is extended at an angle of about forty-five degrees with said shaft, instead of being at a right angle, as usual. The object of so arranging the crank is to enable the operator to turn it without hitting the rim or edge of the tub to which the machine is clamped, whether the tub be square or round, and whether the machine be placed on its front or its end.

The elastic coverings B here shown are made of rubber, and they may be cured on the shafts, or they may, if preferred, be put on after they are cured.

When the machine is used for washing dirt out of clothes the rollers should have an alternating motion—or, in other words, a reciprocating rotary motion—and I accomplish this result by substituting for the worm E a double cam, E', formed on the circumference of a shaft which is supported in the bearings provided for the worm, and is operated by the same crank. Fig. 4 shows one division of the cams, the other being like it in form, and being placed on the opposite side of the shaft, so that each will produce the like motions in the rollers.

The operation of the cams is as follows: The shaft on which they are placed being turned continuously, the roller whose teeth are first engaged by the cam will be rotated a short distance in one direction, and then an equal distance in the opposite direction, and then an equal distance in the first direction, when the tooth slips off the flange of the cam, and the next tooth engages it and goes over the same course. The same cam also engages one of the teeth of the other roller later in its course, and produces the same motions in that roller, but not at the same instant of time, the course of the cam causing one roller to be rotated in

one direction while the other roller is being moved in the contrary direction, and so causing friction on the clothes which are between them, the degree of which friction is determined by the pressure applied from the temper-screw above. There being two cams E' on the same shaft, it follows that these alternating or reciprocating movements of the elastic rollers will be rapidly repeated by turning the crank I.

It will be observed that, by means of the devices above described for moving the elastic rollers, the said rollers are moved simultaneously without being geared to each other, and that the upper one is allowed to rise and fall without interfering with its operation.

The upper roller is allowed to play freely in the slot which receives its journals whenever a greater mass or thickness of clothes is placed at one end than at the other, the spring-bar G, which holds it down, being itself acted on by a single screw in the middle of its length, so that its ends are free to move vertically about the end of the screw without displacing it.

The set-screws in the clamping-fingers K' can be always made to bear at right angles against the sides of the tub or tank to which the machine is attached, because the said fingers are free to turn in their sockets.

I claim as new and desire to secure by Letters Patent—

1. The combination and arrangement of the slotted frame A, dovetail-rail F, spring-bar G, springs H, fingers K K', sockets J, capped wringers B, toothed wheel D, and worm E, substantially as described, for the purpose specified.

2. Making the shafts of the rollers of a skeleton or spider, the angles between whose radial arms are filled in with blocks of larger size than the spaces, substantially as above described.

3. The cams E', made substantially as described, for giving a reciprocating rotary motion to the elastic rollers, so as to produce friction on the clothes placed between them, substantially as set forth.

EDWIN CHESTERMAN.
